United States Patent Office.

J. McILVAIN, OF TENNESSEE, ILLINOIS.

Letters Patent No. 90,112, dated May 18, 1869.

IMPROVEMENT IN CULTIVATORS.

The Schedule referred to in these Letters Patent and making part of the same.

To all whom it may concern:

Be it known that I, J. McILVAIN, of Tennessee, in the county of McDonough, and State of Illinois, have invented new and useful Improvements in Cultivators; and I do hereby declare that the following is a full and exact description of the same, reference being had to the accompanying drawings, and to the letters of reference marked thereon.

This invention relates to cultivators, and consists, mainly, in certain details of construction, which will be fully described hereinafter, by means of which a more efficient and desirable machine is produced.

I term this machine the "Hancock Cultivator."

In the drawings—

Figure 1 represents a side view, and

Figure 2, a plan view of my improved cultivator.

Figure 3, sheet 2, represents a plan view of one cultivator, with certain modifications of construction.

Figure 4, a side elevation of the same.

To enable those skilled in the art to which my invention appertains, to make and use the same, I will now proceed to describe its construction and operation.

A represents the axle of the machine, resting upon the wheels A', which is curved, as shown, to give sufficient room beneath for the necessary movement of the plows,

B B' represent a frame resting upon the axle A, and extending forward, as shown, to which is attached the pole B².

Hanging from the front beam B', of the frame, are the peculiar-shaped beams C, which form both uprights and braces, and which are constructed of a single piece of wrought-iron.

The upper end of the upright part of these beams is secured in a socket by means of a bolt, as shown, by which arrangement, a connection of great stiffness is made.

The rear end of the brace-part of the beam is securely attached beneath the axle, as shown.

By means of holes in the latter, and sockets in the front beam of the frame, the beams C are easily adjusted for cultivating different widths of rows.

D represents the plow-beams, to which the plows are attached.

These are fastened on their front ends to the beams C, as shown, by means of the clevis d, suitable holes being made in the former for adjusting the plows for working at different depths.

By means of this attachment, the plows can be easily swung to one side, if desired, the beam turning upon the bolt which attaches it to the clevis, or the plows may be elevated, the clevis turning upon the bolt which attaches it to the standard.

The rear ends of the plows are elevated, when desired to move to and from the field, by means of the chains d', which catch within the hooks upon the upper beam of the frame, as shown.

It will be observed, that the plows are peculiarly

arranged in regard to the beam, the front plow being placed upon the inside of the beam, the middle plow beneath the beam, and the rear plow upon the outside.

By this arrangement, the plows are located in a diagonal line opposite each other, or, when only two plows are used, following each other.

E represents a shield, placed upon the inside of the front plow, by means of which the corn is protected.

F represents a foot-piece, and

F', a handle, by either of which the plows may be elevated when desired.

H represents an adjustable seat, which slides upon the centre-bar of the frame, as shown, and which may be drawn out when wanted for use.

The arrangement of this is such, that when the plowman is seated thereon, the corn can be easily seen.

By the construction and arrangement herein described, an efficient machine is produced. It is simple in construction, being composed of few parts, and, at the same time, it is exceedingly strong and durable.

The operation will be easily understood.

The front ends of the plows having been properly adjusted, by the means described, (the distance between the beams C having been previously regulated,) motion is communicated to the machine.

The plowman now swings the plows from side to side, or elevates them, as circumstances may require, either riding or walking, as he may choose.

In sheet 2 is shown one cultivator, with certain modifications of construction, which will now be described.

I represent beams, corresponding to beams C in sheet 1.

Instead, however, of being attached to the front beam in the manner before described, they may be provided with an arm, extending, at right angles, in an inward direction, which arm rests upon the beam, as shown.

The end of this arm is provided with a hole for the reception of a bolt.

i represents a short arm, provided with a slot, and having also a hole for the reception of a bolt, which is slipped over the standard I, before it is placed in position.

i' represents the bolt, by means of which the fastening is completed, as is clearly shown in the drawing.

By this arrangement, the beams are firmly held, while, at the same time, their rear ends are permitted to swing laterally, if desired.

The rear ends of the braces I are held by bolts J, the heads of which are caught in recesses in the beam K, the axle-plate being slotted for that purpose.

This slot extends in line with the axle, as shown, and thus permits lateral adjustment of the braces, by means of which the position of the plow is changed.

For the purpose of adjusting, also, the chains,

which hold the rear ends of plow-beam, I provide the screw-hooks K, which may be moved laterally in the slots k, in the cross-beam K'.

I represents the seat, which is attached to the seat-arm L', by means of the bolt l.

The arm L' is slotted, for the purpose of permitting the seat to be adjusted forward or rearward, as may be desired.

The seat-arm is secured in place by means of the pin m, which rests in a corresponding socket in the end of the tongues, and a band, n, as shown.

By elevating the seat until the pin is lifted out of the socket, it may be displaced by drawing it back.

Having thus fully described my invention,

What I claim, and desire to secure by Letters Patent of the United States, is—

1. The standard and brace I, when attached at front and rear as described, for the purpose set forth.

2. The crew-hooks K, when arranged as described, for the purpose set forth.

This specification signed and witnessed, this 26th day of January, 1869.

J. McILVAIN.
